UNITED STATES PATENT OFFICE.

WILLIAM H. AYER, OF CLAREMONT, NEW HAMPSHIRE.

SHUTTLE-CHECK FOR LOOMS.

No. 872,782.

Specification of Letters Patent.

Patented Dec. 3, 1907.

Application filed May 17, 1907. Serial No. 374,220.

To all whom it may concern:

Be it known that I, WILLIAM H. AYER, a citizen of the United States, residing at Claremont, in the county of Sullivan and State of New Hampshire, have invented certain new and useful Improvements in Shuttle-Checks for Looms, of which the following is a specification.

My invention relates to improvements in shuttle checks for looms, and refers in particular to that class of looms in which the shuttle checking is accomplished by the action of the check on the picker stick. In this connection, the invention is applicable to looms in which the picker is connected with the picker stick, or in which the picker runs on a picker rod.

The principal object of my invention, is the provision of a shuttle check of extremely simple and durable construction which will effectually cushion the impact of the shuttle on the picker and hold the picker stick and consequently the picker and shuttle from rebounding, thereby preventing any loss in the shuttle-throwing power and being of great benefit to the loom.

Another object of my invention, is to provide a shuttle check which will position the picker stick and consequently the picker directly in line with the shuttle point, thereby making it impossible for the shuttle to wear the picker in the wrong place, as the improper wearing of the picker would eventually cause the shuttle to fly out of the loom.

My invention also has for its object the provision of a check which is adjustable and may be adapted to the lays of various types of looms, and a further object of the invention is the provision of a check possessing the above attributes which shall be entirely practical and efficient in every respect.

With the above and other objects in view, my invention consists broadly of spring braking members adjustably mounted upon the lay of the loom having inwardly flaring portions to engage and retard the motion of the picker stick, and guiding means for the free ends of the spring retarding members.

The invention further comprises a shuttle check embodying certain other novel features of construction, combination and arrangement of parts substantially as disclosed herein and illustrated in the accompanying drawings, in which:

Figure 1, is a side elevation of one end of the lay of a loom having my improved shut-

tle check applied thereto, the picker stick being indicated in dotted lines. Fig. 2, is a bottom plan view of the same, the picker stick being omitted. Fig. 3, is a detail end view partly in section of a slightly modified form of supporting bracket for the spring retarding members. Fig. 4, is a detail view of a modified form of guide for the ends of the resilient spring members.

In the drawings: The numeral 1, designates one end of an ordinary lay which is provided with the usual slotted race or guide-way 2, in which the picker stick 3, plays back and forth. Affixed to the lay inward from the end thereof, by the bolts or other suitable fastenings 3', are the pair of oppositely-disposed depending brackets 4. Flat steel springs 5, have their ends secured to the depending portions of the supporting brackets by fastening bolts 6, and these supporting brackets are provided with a lateral wing extension 7, in which are mounted the adjustable set screws 8, the inner ends of these set screws bearing upon the spring members to force the same inward and adjust the tension thereof. Lock nuts 9, are preferably arranged upon the outer portions of the set screws to hold them in adjusted position.

From their point of support, the flat spring members are directed inwardly or toward the race on a gradual curve as at 10, to a converging point 11, where the spring members are preferably in light contact with each other. From their point of probable contact, the points or ends of the springs are flared outwardly as at 12. To the inner wearing faces of the springs near the free ends thereof, are usually secured the layers of leather or other suitable frictional material 13, such frictional surface being held in place by rivets 14, or other suitable fastening means may be employed.

A depending guiding loop 15, is mounted at the outer end of the lay which surrounds the free flaring ends of the springs to prevent unusual spreading of the same and to hold the springs in contact with the picker stick when the stick is in position therebetween. Depending from the extreme end of the lay, is a stop 16, having a narrow depending guiding finger 17, which serves to separate the free ends of the spring retarding members and keep the ends of the members centrally located with respect to the race.

In the modification illustrated in Fig. 3, the supporting brackets for the spring re-

tarding members, are formed with an angular inwardly directed extension 21, which passes beneath the lay, and pivotally secured to said angular extensions by means of the 5 fastening screws or bolts 22, are the supplementary supporting brackets 23, which are each provided with the lateral wing extensions and set screws as before described, such last-named parts being designated by the numerals 7, and 8, occurring in Figs. 1 and 2. This form of supporting bracket is thus made in two parts; the lower part being rotatably adjustable with respect to the upper part, so that the tension of the retarding spring 10 may be roughly adjusted by shifting the lower portion of the supporting bracket and then completing the adjustment by means of the set screw.

As illustrated in Fig. 4, the guide for the 20 free ends of the spring retarding arms may be formed of one continuous piece, the same consisting of a resilient flat plate having a narrow attaching portion 24, and a widened lower portion 25, having parallel slots or 25 openings 26, therethrough to receive the flaring ends of the spring members. The comparatively thin strip 27, between the parallel openings in the guiding plate prevents the free flaring ends of the spring 30 members from approaching each other too closely, while the outside boundaries to the parallel openings limit the spreading tendency of the spring members.

In the operation of the device, the spring 35 arms bear against the picker stick in its return stroke about two inches from its rear normal position, then when the shuttle strikes against the picker which is carried by the front of the picker stick, the shuttle will 40 force the picker stick back to the limit of the picker stick race, and the spring arms bearing against the picker stick, will cause the picker stick, picker and shuttle to be brought to a complete, gradual and easy stop without 45 any rebound of the parts. The check thus yields gradually to the impact of the shuttle on the picker and cushions the impact. The tension of the spring members with respect to the picker stick may readily be adjusted at any time by means of the set screws.

From the foregoing description taken in connection with the drawings, it will be readily apparent that I have provided a 55 shuttle check which accomplishes all the results herein set forth as the objects of the invention, and which is practical and satisfactory in every respect.

I claim:

60 1. The combination with the lay of a loom,

of angular brackets depending therefrom, flat springs secured to said brackets having converging portions, and set screws mounted in the brackets to engage the springs for adjusting the tension of said springs. 65

2. The combination with the lay of a loom, angular brackets depending therefrom, of spring members adjustably secured to said brackets and having converging portions, a guiding loop surrounding the free ends of the 70 spring members, and an abutment located between the sides of the loop for holding the ends of the members in spaced relation. 70

3. A shuttle check comprising angular 75 brackets having a horizontally adjustable supporting portion, converging spring members carried by said supporting portions and set screws mounted in the supporting portions to engage the spring members to adjust the tension thereof. 80

4. In a shuttle check, the combination with spring retarding members, of a guiding plate having openings therein to receive the free ends of the spring members and form a guide for such free ends, the guiding openings in the plate being separated by a comparatively thin strip which acts as an abutment to keep the ends of the spring members properly spaced. 85

5. The combination with the lay of a loom, 90 of angular brackets depending therefrom, the brackets having a lateral extension parallel to the lay, flat springs secured to the bracket, set screws carried by the lateral extensions to regulate the springs, the springs having 95 curved converging ends faced with friction material, a guiding loop depending from the lay surrounding the free ends of the springs, and an abutment arranged between the ends of the springs to hold the same spaced apart. 100

6. The combination with the lay of a loom, 105 of angular brackets depending therefrom, the brackets having a lateral extension parallel to the lay, flat springs secured to the brackets, set screws carried by the lateral extensions to regulate the springs, the springs having curved converging ends faced with friction material, a flat plate depending from the end of the lay having guiding openings therein to receive the ends of the springs, the 110 guiding openings being separated by a strip which strip acts as an abutment to hold the ends of the springs spaced apart.

In testimony whereof I affix my signature in presence of two witnesses.

WILLIAM H. AYER.
